United States Patent Office

Des. 178,449
Patented Aug. 7, 1956

178,449

NECKTIE

Robert R. Brown, Monmouth County, N. J., assignor of one-half to Sverre Sorenson, Atlantic Highlands, N. J.

Application July 13, 1955, Serial No. 36,952

Term of patent 14 years

(Cl. D3—16)

Fig. 1.

Fig. 2.

Fig. 1 is a front view of a necktie showing my new design; and

Fig. 2 is a cross section on the line 2—2 of Fig. 1.

The essential features of my design reside in the portions shown in solid lines on the drawing.

The undisclosed side of the necktie is plain and unornamented.

I claim:

The ornamental design for a necktie, as shown and described.
